DESIGN FOR A COMBINED DESK LAMP AND DISPLAY CASE

Leon W. Terry, Flint, Mich., assignor of two-thirds to M. V. Terry, Flint, Mich.

Application April 5, 1945, Serial No. 118,869

Term of patent 14 years

(Cl. D48—20)

To all whom it may concern:

Be it known that I, Leon W. Terry, a citizen of the United States, residing at Flint, Genesee County, Michigan, have invented a new, original, and ornamental Design for a Combined Desk Lamp and Display Case, of which the following is a specification, reference being had to the accompanying drawing, forming a part thereof, in which:

Fig. 1 is a front elevation, Fig. 2 is a top plan view, and Fig. 3 is a side elevation of a combined desk lamp and display case embodying my design.

I claim:

The ornamental design for a combined desk lamp and display case, as shown.

LEON W. TERRY.
